UNITED STATES PATENT OFFICE.

CLYDE EDSON WHEELER, OF GULL LAKE, SASKATCHEWAN, CANADA.

ATTACHMENT TO HARNESS.

1,139,829.

Specification of Letters Patent.

Patented May 18, 1915.

Application filed April 8, 1914. Serial No. 830,488.

To all whom it may concern:

Be it known that I, CLYDE EDSON WHEELER, of the town of Gull Lake, in the Province of Saskatchewan, Canada, have invented 5 certain new and useful Improvements in Attachments to Harness, of which the following is the specification.

The invention relates to improvements in harness especially to a harness strap fastening and the object of the invention is to provide a device to be used with the side breeching strap of a set of harness and applied at the point where the breeching strap is connected to the collar, said device preventing the wearing and consequent cutting 10 of the breeching strap where the same is connected to the collar.

With the above object in view the invention consists essentially in a flexible strap 20 having two cross slots therein and an end slit and the body portion thereof contracted between the slots, the parts being arranged and constructed as hereinafter more particularly described and later pointed out in the 25 appended claims.

Figure 1 represents a perspective view of the device as in use. Fig. 2 represents a top view of the same, the hames being shown in horizontal section. Fig. 3 represents a face 30 view of the strap detached.

In the drawing like characters of reference indicate corresponding parts in each figure.

1 represents the ordinary horse collar and 35 2 one of the hames applied on the collar in the usual way and carrying the customary rings 3, 4 and 5 connected to the hames by eye bolts 6. 7 represents a tug connected with the hames and 8 represents a side 40 breeching strap having the forward end turned back on itself to form a loop 8' and fastened by means of a buckle 8''. The 45 above parts are of ordinary construction.

Customarily the forward end of the side 50 strap is simply looped through the ring 4. The result of this is that the ring, being in direct contact with the strap will in time cut it and the inner face of the strap will also be badly worn in constant use in rubbing against the collar.

My invention has for its object as already referred to the provision of a means to prevent the cutting of the strap by the ring and the wearing of the same by the collar. 55 I accomplish this by the provision of a wearing strap 9 fitted with an end cross slot

10, a central cross slot 11 and an end slit 12, the strap having also that portion of the body thereof between the cross slots contracted as indicated at 13.

In applying the wearing strap it will be seen that the sides of the loop of the side strap are passed through the slots 10 and 11 while the slit 12 is passed over the ring. By so applying the wearing strap there is 35 a portion of it brought between the ring and the looped end of the side strap and a further portion of it located between the inner side of the loop of the side strap and the face of the collar.

Under working conditions it is obvious that the wearing strap will be cut by the ring and worn by the collar and the breeching strap will be kept intact. After the wearing strap has been worn out a new one 75 can be readily supplied at small cost. The body of the wearing strap is contracted at 13 so that it will better fit the ring.

What I claim as my invention is:—

1. The combination with the hame of a 80 horse collar provided with the usual side strap ring and a side strap connected to the ring by a loop, of a wearing strap applied on the side strap and passing between the loop of the strap and the ring and between 85 the inner side of the loop and the face of the collar, as and for the purpose specified.

2. The combination with the hame of a 90 horse collar provided with the usual side strap ring and a side strap connected to the ring by a loop, of a wearing strap having a portion thereof inserted within the loop of the side strap and bearing on the ring and a portion thereof extending between the loop of the side strap and the collar and connected to the hame, as and for the purpose 95 specified.

3. The combination with the hame of a 100 horse collar provided with the usual side strap ring and a side strap connected to the ring by a loop, of a wearing strap passed through the ring between the loop of the side strap and the ring and having cross slots therein receiving the sides of the loop and an extending end passed between the inner side of the loop and the collar and fastened to the hame, as and for the purpose 105 specified.

4. The combination with the hame of a 110 horse collar provided with the usual side strap ring fastened by an eye bolt to the hame and a side strap looped through the

- ring, of a wearing strap looped through the ring between the loop of the side strap and the ring and having cross slots therein receiving the sides of the side strap loop and being provided further with an extending slotted end located between the inner side of the loop and the collar, said slotted end being passed over the ring and anchored on the eye bolt, as and for the purpose specified.
- 10 5. A wearing strap for harness having a longitudinal slot in one end of sufficient length to slip over a strap ring in one end, a cross slot in the opposite end of sufficient width to receive the harness strap and an intermediate cross slot also of sufficient width

15 to receive the harness strap as and for the purpose described.

6. A wearing strap having a cross slot in one end, a longitudinal slit in the other end, an intermediate cross slot in the body portion and the body portion thereof between the cross slots contracted, as and for the purpose specified. 20

Signed at Winnipeg this 18th day of March, 1914.

CLYDE EDSON WHEELER.
